UNITED STATES PATENT OFFICE.

EDWARD CURRAN, OF CARDIFF, WALES.

MUFFLE-FURNACE.

1,114,587.

Specification of Letters Patent. Patented Oct. 20, 1914.

Application filed March 21, 1914. Serial No. 826,342.

To all whom it may concern:

Be it known that I, EDWARD CURRAN, a subject of the King of Great Britain, residing at Cardiff, Wales, and whose post-office address is 72 Bute street, Cardiff, in the county of Glamorgan, Wales, have invented certain new and useful Improvements in Muffle-Furnaces, of which the following is a specification.

This invention relates to muffle furnaces and in particular to the arrangement of the heating flues and the control of the gases traversing them. According to the present invention these arrangements are such that the heating gases may be caused to traverse a flue or flues over the muffle (which may be constructed of solid or hollow brickwork) and pass thence direct to a flue or flues under the muffle through a downtake or downtakes controlled by dampers operable from outside; or the gases may be caused to pass around the back and along the sides of the muffle and thence through downtakes controlled by dampers to the flue or flues under the muffle and so to the chimney; or the heating gases may divide immediately after leaving the furnace or combustion space or after passing through a firebrick arch such as described in my United States Patent No. 1,015,616, dated January 23rd, 1912, part of the gases following the former, and the remainder the latter of the two courses above indicated; or the heating gases may be caused to follow either of these courses but may be confined more or less to either side of the furnace by having a symmetrical arrangement of flues on the two sides of the central longitudinal vertical plane of the muffle. Further, the floor of the muffle may be built of the hollow bricks so as to provide passages in the muffle floor through which hot gases may pass from the fire arch or combustion space and thence into the main flue or flues under the furnace floor, these passages in the muffle floor being controlled by dampers which may be fitted below the mouth of the muffle.

Within the transverse flue at the back of the muffle there may be a wall extending more or less parallel with the rear wall of the muffle but separated therefrom so as to leave a space or cavity between them to prevent excessive heating of the rear end of the muffle.

In the accompanying drawings Figure 1 is a longitudinal section of a furnace em-

bodying the present invention; Fig. 2 a sectional plan of the same; Fig. 3 a section on line 3—3 of Fig. 1; Fig. 4 a part section on line 4—4 of Fig. 1; Fig. 5 is a horizontal section through the flues; Fig. 6 represents longitudinal sections of a portion of the fire arch taken on the line 5—5, Fig. 1, and looking respectively in opposite directions, and Fig. 7 is a longitudinal section on the line 7—7 of Fig. 2, that is, through a side flue and the downtakes leading to a bottom flue.

In these drawings a furnace is shown with a single top flue *a* extending longitudinally over the entire length and width of the muffle with a downtake *b* controlled by a damper *c* at each side near the end of the furnace sitting away from the fire grate *d* or combustion chamber, each downtake leading to a longitudinal flue *e* extending under the muffle *f* back toward the fire grate or combustion space, and thence to the main chimney flue *g*. Further, there is a transverse flue *h* at the back of the muffle and approximately on the same level as the muffle floor, leading to longitudinal flues *i* along each side of the muffle which in turn communicate, through downtakes *j* controlled by dampers *k*, with the two longitudinal flues *e*, *e* under the muffle. The side flues *i* are separated from the top flue *a* each by a flue roof wall *l*, Fig. 7.

The floor *m* of the muffle may be built of hollow bricks so as to provide passages *n* within the muffle floor through which the hot furnace gases may pass from the transverse flue *h* and, after traversing the passages in the muffle floor, pass downward therefrom through downtakes *o* controlled by dampers *p* and thence into the main flue or flues *e* under the furnace floor.

Within the transverse flue *h* at the back of the muffle there may be a wall *l* extending more or less parallel with the rear wall of the muffle but separated therefrom so as to leave a space or cavity between them to prevent excessive heating of the rear end of the muffle.

As shown more particularly in Fig. 3 the arch or roof *q* of the muffle is supported entirely by fire burs *r* projecting from the side walls of the furnace structure so that the sides *s* of the muffle or the roof *q* can be renewed or repaired without disturbing the roof or the sides respectively.

Above the grate *d* is a fire arch *w*, constructed as described in the above-men-

tioned U. S. patent specification, and formed of firebricks disposed and keyed one into the other so as to constitute an arch having a number of vertical passages w' and continuous longitudinal passages w^2 , Figs. 1 and 6, which communicate with the atmosphere through an opening or openings α in the furnace wall.

The ashpit t of the furnace is provided with doors u so as to enable the primary air supply to the furnace to be cut off altogether except in so far as there may be some leakage through the doors of the fire rake ports v .

It is assumed that under these conditions the radiant energy from the fire arch w effects the continued distillation of the fuel on the grate d , combustion of the gaseous products taking place in the arch in the space above and below it. Under these conditions of working, namely with the primary air supply cut off entirely by the ashpit doors u and only the secondary air being admitted to the various ducts in the fire arch w through secondary air ports one of which is indicated at α , it is necessary to modify the chimney draft and consequently a main flue damper y is introduced in the chimney flue which is closed to the extent of about $\frac{1}{4}$ or even more in order to maintain an approximation to the temperature which can be obtained in the furnace when working with open ashpit and full chimney draft; or the damper may be closed altogether and yet combustion continue in the furnace sufficiently actively to maintain a high temperature once the furnace has been thoroughly heated up.

It is to be understood that many modifications may be made in the construction of the improved furnace without exceeding the scope of the present invention; for example, the numbers of longitudinal flues above and below the muffle may be varied according to the dimensions of the furnace, and the positions of the controlling dampers may also be altered to suit particular conditions of working or constructions of furnace, the essential feature being that absolutely complete control of the heating gases can be obtained so that the muffle can be heated mainly along the top and either toward one or both sides of the same, or mainly along the side walls and either on one or both sides,

or mainly along the floor and either on one or both sides of the same, or any combination of these conditions can be secured by the improved construction of furnace.

Having now particularly described and ascertained the nature of my said invention and the best means I know of carrying the same into practical effect, I claim:—

1. A muffle furnace having top, side and bottom flues for heating the furnace, down-takes connecting the top and bottom flues, separate down-takes connecting the side and bottom flues, and controlling dampers in said down-takes whereby the heating gases can be simultaneously distributed through all the flues and alternatively can be confined to the top and bottom flues or to the side and bottom flues only.

2. A muffle furnace having a combustion space, a top flue for conducting gases from the combustion space above the muffle roof, separate side flues for conducting gases from the combustion space along the side walls of the muffle, a flue formed in the floor of the muffle, longitudinal flues to receive gases from the flues before mentioned and conduct such gases beneath the muffle and thence to a chimney, and controlling dampers in each of the top, side and floor flues whereby the gases can be simultaneously distributed through them or confined to either one or more of them.

3. A muffle furnace having a combustion chamber in rear of its rear wall, heating flues leading from said chamber and arranged on the top and sides and below the bottom of the muffle, a transverse partition wall between the said chamber and the rear wall of the muffle, a second transverse wall extending between the side flues and disposed between the said partition wall and the rear muffle wall, said second transverse wall being substantially parallel with the rear muffle wall and forming an air space with it.

In testimony whereof I have signed my name to this specification in the presence of two subscribing witnesses.

EDWARD CURRAN.
